UNITED STATES PATENT OFFICE.

DANIEL C. HALL, OF BOSTON, MASSACHUSETTS.

DESIGN FOR A MILITARY SHOULDER-KNOT.

Specification forming part of Design No. 5,967, dated July 2, 1872.

To all whom it may concern:

Be it known that I, DANIEL C. HALL, of Boston, in the county of Suffolk and State of Massachusetts, have invented or produced an Improved Design for a Military Shoulder-Knot; and I do hereby declare that the following, taken in connection with the drawing which accompanies and forms part of this specification, is a description of my invention sufficient to enable those skilled in the art to produce it.

My invention relates to a new form to be given to a military shoulder knot or strap, intended particularly for (musicians of) military bands.

In my improved design I form the knot or shoulder device as a metal hemisphere, preferably using a thin plate metal, the outer surface of which I burnish or polish to form a bright and glittering surface, and I fasten this device to a bar that lies upon the shoul-

der of the coat, and has at its inner end a button by which it is secured to the shoulder.

My invention consists in this improved design, and the drawing shows a device embodying it.

a denotes the metal hemisphere, fastened to a bar, *b*, that lies upon the shoulder, as seen at A, and terminating in a button, *c*.

The device is light, unique, and very showy, and is particularly well adapted for the use of military bands.

I claim—

The new design for a military shoulder-knot, consisting in the hemispherical projection *a* at the end of the bar *b*, substantially as shown and described.

D. C. HALL.
